UNITED STATES PATENT OFFICE.

HARRY M. PIERCE, OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

CARTRIDGE-LOADING MACHINE.

1,082,137.

Specification of Letters Patent.

Patented Dec. 23, 1913.

Application filed September 2, 1911, Serial No. 647,344. Renewed May 21, 1913. Serial No. 769,093.

To all whom it may concern:

Be it known that I, HARRY M. PIERCE, a citizen of the United States, residing at Wilmington, county of Newcastle, and State of Delaware, have invented a new and useful Improvement in Cartridge-Loading Machines, of which the following is a full, clear, and exact description, reference being had to the accompanying drawings, which form 10 a part of this specification.

The invention relates to dynamite cartridge filling machines of the type disclosed in the Hall Patent No. 601,138, issued March 22, 1898, and the Donaldson Patent 15 No. 899,592 issued Sept. 29, 1908. The present invention, however, relates only to the anti-friction driving mechanism for operating the tamps, the object being to provide means for uniformly and accurately packing 20 the dynamite into shells of any required number or size. I do not, therefore, illustrate or describe the entire machine, but only that part thereof to which the invention relates.

25 In the drawings: Figure 1 is a sectional elevation of mechanism for operating a single row of tamps. Fig. 2 is a sectional plan on the line 2—2 of Fig. 1. Fig. 3 is a sectional elevation of part of the mechanism 30 for operating a double row of tamps; Fig. 4 is a side elevation of modified form of mechanism for operating the cams for resetting the dogging mechanism.

35 *a* is the machine frame. Bolted to the frame are bearings *b*' for the shaft *b*, to which are secured eccentrics *c*. A cross-head *d*, sliding in vertical guides *d*' is connected with and reciprocated from eccentrics *c* by means of connecting rods *e*. In the 40 machine of Fig. 1 there is a single row of tamping rods *f* sliding vertically in guides *f*', *f*'' on the frame. To these rods are attached extensions (not shown) adapted to enter the cartridges and pack the powder 45 therein.

Secured to cross-head *d* are shafts *g* carrying bearing blocks *h*. These blocks have a revolving motion upon shafts *g* and a sliding motion in the toggle rolling cams *i*. 50 A pair of such toggle rolling cams is provided for each tamping rod *f*. These toggle rolling cams are held in position upon shafts *g* by means of collars *i*' and are fulcrumed at their outer ends to blocks *j* adjustable in supports and guides *k* on the machine

frame. Caps *k*' are secured to supports *k* and hold the blocks *j* in place. In each support *k*, to the rear of block *j*, is placed a spring *k*'' tending to force out the corresponding block. An adjusting screw *k*'' carries a disk *k*'' abutting against the rear of the spring *k*''. By means of this screw, the tension of the spring against its corresponding block may be regulated. Toggle levers *l* are fulcrumed to brackets *j*' on adjustable 60 blocks *j*. The toggles of each pair are jointed together at their inner ends. Vertically extending dogging rods *m* (one for each tamping rod *f*) are jointed to the several pairs of toggle levers *l*. The rods *m* slide 65 in guides *f*'. A rigid bar or stop *n*, secured to the frame, is arranged beneath the toggle levers *l*. On each tamp rod *f* is a loose 70 block *o* provided with a tongue having a sliding fit in a slot *o*' in the tamp rod. The 75 upper ends of the dogging rods *m* rest against a rigid bar *q*. Turning in bearings *p* in the frame is a shaft *p*, to which is secured a double cam *r*, *r*', one member *r* of which bears against dogging levers *s*, while 80 the other member *r*' is adapted to engage arms *m*' projecting laterally from the upper ends of dogging rods *m*. The dogging 85 levers *s* are pivoted between their ends to the dogging rods *m*. The lower ends of the 90 levers *s* are normally pressed against cam member *r*' by means of springs *s*', which also act to press the dogging rods *m* against rigid bar *q*. The upper ends of dogging 95 levers *s* rest against the tamp rods *f*. On the shaft *p* is a spur gear *p*'' engaging a spur gear *t*'' on a shaft *t*, to which is secured a hand operating lever *t*'.

The operation of the above mechanism is as follows: The drawings show the mechanism during the operation of filling the shells. The shafts *b*, through eccentrics *c*, connecting rods *e*, cross-head *d*, shafts *g* and blocks *h*, imparts rocking motion to toggle rolling cams *i* on their adjustable blocks *j*. At each downward stroke of the cross-head *d* the tamp rods *f* are carried down by the cams *i* and the extensions of the rods touch the powder in the shells and pack it until a given resistance is encountered, after which the tamp rods remain stationary, slipping between opposing curved faces of the cams. During the upward stroke of the cross-head *d*, the tamp rods are lifted by the cams. It will thus be understood that at each com- 105 110

plete oscillation down and up of the cams *i*, each tamp is lifted a net distance equal to the amount of powder packed in the corresponding shell. The loose sliding blocks *o* are consequently lifted slightly higher at each upward stroke of the cross-head. When any given shell is packed to its full extent, the block *o* of the corresponding tamp rod *f* will have been lifted sufficiently high to engage and override the corresponding dogging lever *s*. During the upward strokes of the tamp rods *f* the blocks *o* rest upon the bottoms of the slots *o'*; but after any block has been lifted, as described, into engagement with its respective dogging lever *s*, it will be carried, during the following downward movement of its tamp rod *f*, into position at the upper end of the slot *o'*; after which, before the completion of the downward movement of such tamp rod, the said block *o* will be carried down therewith and apply sufficient pressure upon the dogging lever *s* and dogging rod *m* to force the corresponding pair of toggle levers *l* down against the stop-bar *n* and into a straight line position, thereby forcing back the corresponding adjustable blocks *j*, which retract the corresponding toggle rolling cams *i* from the corresponding tamp rod *f*. Thereafter, the said tamp rod is at rest, the corresponding toggle roller cams vibrating as before but not touching the tamp rod. When any particular pair of toggle rolling cams *i* has thus been rendered inoperative, the corresponding tamp *f* has not been carried down to the extent that it would have been had the cams *i* not been rendered inoperative and had the block *o* not been stopped by the dogging mechanism; but the lower end of the extension (not shown) of said tamp is about (say) four and one half inches above the top of the powder in the corresponding shell and is therefore in position for operation as soon as the filled shells are removed and empty shells placed in position ready for the next operation. After all the shells are filled and hence the cams *i* rendered inoperative and a set of empty shells placed in position, the operation is started as follows: By means of the operating lever *t'* and the spur gear connection between shafts *t* and *p*, the cam *r*, *r'*, is turned, causing member *r'* to move all the loose sliding blocks *o* and allow them to slide down into resting position as shown, and allowing all the tamp rods *f* to descend until they rest against the bottoms of the empty shells. At the same time, the cam member *r* engages arms *m'* and lifts dogging rods *m* and toggle levers *l*, allowing springs *k* to press blocks *j* and cams *i* against the tamping rods *f*. The arrangement is such that, in the movement of the lever *t'*, the undogging of the tamping rods

f occurs at the same time that the cams *i* engage the tamping rods, whereby the latter are carried down by the cams to the bottoms of the empty shells at the end of the down stroke, thus preventing the tamping rods from falling. The machine continues to operate and each tamping rod continues to tamp its respective shell until it is dogged as hereinbefore described.

The mechanism of Fig. 3 differs from that of Figs. 1 and 2 only in that it is adapted to actuate a double row, instead of a single row, of tamps. The various parts of similar construction are similarly lettered in the two sets of figures. The only substantial differences are the following: In the double-row mechanism, the toggle levers *l* of a pair are not jointed together, but each is jointed to one of the pair of dogging rods *m* and their inner ends bear against the rigid bar *v*. A rectangular bar *w* is secured to the cross-head *d* and extends between the two rows of tamp rods *f*, the latter sliding between this bar and the cams *i*. There are, of course, provided two cams, one for each set of dogging levers and dogging rods. These cams are mounted respectively on the shafts *x* and *x'*. The shaft *x* is driven from the shaft *x*, through the medium of spur gears *x* and *x'*. Spur gear *x* drives gear *x'* and also gear *x* on shaft *x'*. On the shaft of gear *x* is the hand operating lever *x'*.

In Fig. 4 is shown a modified and simplified means for turning the cams that actuate the dogging levers and rods. The cams are secured respectively to the shafts *y* and *y'*, which are geared together directly by the spur gears *y* and *y'*. The hand operating lever may be applied to either shaft *y* or shaft *y'*.

The degree of hardness of packing in the shells is regulated by screwing or unscrewing the adjusting screws *k*, thereby, through blocks *j* and cams *i*, increasing or diminishing the pressure against the tamping rods *f* and thus varying the resistance of the rods to slippage.

While all the tamps start tamping empty shells at the same time, any variations and irregularities are controlled because the tamping rods and their actuating and undogging mechanisms are independent of each other.

Having now fully described my invention, what I claim and desire to protect by Letters Patent is:

1. In a machine for loading shells, the combination with a series of independent tamping rods, of a series of cams fulcrumed to rock in the direction of extension of the tamping rods, said cams having curved faces adapted to engage and reciprocate the tamping rods but permitting the latter to slip upward under predetermined resistance to

downward movement, means to rock said cams, and independent mechanism controlled by each rod for disengaging the corresponding cam from said rod when the latter has moved up to a determinate extent.

2. In a machine for loading shells, the combination with a series of independent tamping rods, of a series of cams fulcrumed to rock in the direction of extension of the tamping rods, said cams having curved faces adapted to engage and reciprocate the tamping rods but permitting the latter to slip upward under predetermined resistance to downward movement, means to rock said cams, adjustable spring-pressed blocks on which said cams are fulcrumed, and independent mechanism controlled by each rod for moving the corresponding cam and block outward when such rod has moved up to a determinate extent.

3. In a machine for loading shells, the combination with a series of independent tamping rods, of driving means for reciprocating each rod, each of said means being independently movable out of engagement with its corresponding rod, toggle levers for each driving means adapted when moved toward a straight line position to disengage the corresponding driving means from its corresponding rod, independent dogging mechanism for so operating the corresponding toggle levers and means carried by each rod adapted to be lifted above the corresponding dogging mechanism after said rod has been retracted to a determinate extent and operate said dogging mechanism in the downward movement of said rod.

4. In a machine for loading shells, the combination with a series of independent tamping rods and a series of independent normally stationary dogging rods, of independent driving means for reciprocating each tamping rod, independent means carried by each tamping rod adapted to be lifted above the corresponding dogging rod after said tamping rod has been retracted to a determinate extent and operate said dogging rod in the downward movement of said tamping rod, independent mechanism actuated by each dogging rod for disengaging the corresponding driving means from the corresponding tamping rod, and means actuated from a common control to operate all the dogging rods to simultaneously permit all the driving means to reengage their respective tamping rods.

5. In a machine for loading shells, the combination with a series of independent tamping rods, of independent driving means frictionally engaging and adapted to operate each rod, independent releasing means for disengaging each driving means from its corresponding rod, a block having a limited sliding movement on each rod and dogging mechanism, connected with and

operating each releasing means, adapted to be overridden by its corresponding block in the receding movement of its corresponding rod and actuated by said block, in the next forward movement of said rod, to operate the releasing means.

6. In a machine for loading shells, the combination with a series of independent tamping rods, of independent driving means frictionally engaging and adapted to operate each rod, independent releasing means for disengaging each driving means from its corresponding rod, a block having a limited sliding movement on each rod, dogging mechanism, connected with and operating each releasing means, adapted to be overridden by its corresponding block in the receding movement of its corresponding rod and actuated by said block, in the next forward movement of said rod, to operate the releasing means, and means operated from a single control to actuate all the dogging mechanisms to permit all the blocks and rods to drop and render the releasing means inoperative.

7. In a machine for loading shells, the combination with a series of independent tamping rods, of independent driving means engaging and adapted to operate each rod, independent normally inoperative releasing means for disengaging each driving means from its corresponding rod, a normally stationary dogging rod connected with and adapted when actuated to operate each releasing means, a dogging lever pivoted on each dogging rod, a block carried by each rod adapted after the rod has receded to a predetermined extent to abut against the corresponding lever and thereby actuate the corresponding dogging rod and releasing means, and means, operable from a common control, to operate all the levers to release all the blocks and to operate all the dogging rods to render the releasing means inoperative.

8. In a machine for loading shells, the combination with a series of independent tamping rods adapted to be reciprocated in the direction of their length, of a series of cams fulcrumed to rock in the direction in which the tamping rods are reciprocable, said cams having curved frictional faces adapted to reciprocate the tamping rods but permitting them to slip under predetermined resistance to movement, and means to rock the cams.

9. In a machine for loading shells, the combination with a series of independent tamping rods adapted to be reciprocated in the direction of their length, of a series of cams fulcrumed to rock in the direction in which the tamping rods are reciprocable and also movable laterally toward and from the tamping rods, said cams having curved faces adapted to engage and reciprocate the tamp-

ing rods but permitting the latter to slip under predetermined resistance to downward movement, means to rock said cams in unison and independent mechanism controlled by each rod for moving the corresponding cam laterally away from the rods.

10. In a machine for loading shells, the combination with a series of independent tamping rods, of a series of cams fulcrumed to rock in the direction of extension of the tamping rods, said cams having curved faces adapted to engage and reciprocate the tamping rods but permitting the latter to slip upward under predetermined resistance to downward movement, means to rock said cams, laterally slidably blocks on which said cams are respectively fulcrumed, springs normally holding said slidable blocks in position to cause the cams to operatively engage the respective rods, and independent mechanism controlled by each rod adapted in the downward movement of each rod after such rod has moved to a determinate extent, to move the corresponding block against the action of its spring, thereby retracting the corresponding cam.

11. In a machine for loading shells, the combination with a series of independent tamping rods and a series of independent dogging rods, of independent driving means for reciprocating each tamping rod, independent means controlled by each tamping rod adapted, after such tamping rod has been retracted to a determinate extent, to depress the corresponding dogging rod, independent mechanism, actuated by each dogging rod in its downward movement, for disengaging the corresponding driving means from its respective tamping rod, and a cam for simultaneously lifting all the dogging rods to permit all the driving means to reengage their respective tamping rods.

12. In a machine for loading shells, the combination with a series of independent tamping rods and a series of independent dogging rods and a dogging lever for each dogging rod, of independent driving means for reciprocating each tamping rod, independent means controlled by each tamping rod adapted, after such tamping rod has been retracted to a determinate extent, to engage the corresponding dogging lever and depress it and the corresponding dogging rod, independent mechanism, actuated by each dogging rod in its downward movement, for disengaging the corresponding driving means from its respective tamping rod, and a cam adapted to engage and lift all the dogging rods to permit all the driving means to reengage their respective tamping rods and also adapted to disengage all the dogging levers from their respective tamping rods to permit the latter to descend.

13. In a machine for loading shells, the

combination with a series of independent tamping rods, of independent driving means for reciprocating said rod, a block for each rod having a limited sliding movement thereon, independent mechanism for disengaging each driving means from its corresponding rod, said block being adapted when its corresponding rod has moved upward a determinate extent to override the corresponding disengaging mechanism and actuate it in the subsequent downward movement of said rod.

14. In a machine for loading shells, the combination with a series of independent tamping rods, of independent driving means for reciprocating said rod, a block for each rod having a limited sliding movement thereon, independent mechanism for disengaging each driving means from its corresponding rod, said block being adapted when its corresponding rod has moved upward, a determinate extent to override the corresponding disengaging mechanism and actuate it in the subsequent downward movement of said rod, and means actuated from a common control for moving said disengaging mechanisms into position to permit said blocks to drop and permit all said driving means to reengage their respective rods.

15. In a machine for loading shells, the combination with a series of independent tamping rods and a series of independent dogging rods and dogging levers, of independent driving means for reciprocating each tamping rod, a block for each rod having a limited sliding movement thereon and adapted, after its tamping rod has been lifted to a determinate extent, to override the corresponding dogging lever and, in the subsequent downward movement of said rod, depress said dogging lever and the corresponding dogging rod, and independent mechanism, actuated by each dogging rod in its downward movement, for disengaging the corresponding driving means from its respective tamping rod.

16. In a machine for loading shells, the combination with a series of independent tamping rods and a series of independent dogging rods and dogging levers, of independent driving means for reciprocating each tamping rod, a block for each rod having a limited sliding movement thereon and adapted, after its tamping rod has been lifted to a determinate extent, to override the corresponding dogging lever and in the subsequent downward movement of said rod, depress said dogging lever and the corresponding dogging rod, independent mechanism, actuated by each dogging rod in its downward movement, for disengaging the corresponding driving means from its respective tamping rod, and a cam adapted to engage and lift all the dogging rods to permit all the driving means to reengage

their respective tamping rods and adapted also to move all the tamping levers from under their respective blocks to permit said blocks to drop and the tamping rods to be again actuated by their respective driving means.

17. In a machine for loading shells, the combination with a series of independent tamping rods, of a series of cams fulcrumed to rock in the direction of extension of the tamping rods, said cams having curved faces adapted to engage and reciprocate the tamping rods but permitting the latter to slip upward under predetermined resistance to downward movement, a cross-head, guides in which said cross-head reciprocates, a shaft carried by said cross-head, blocks on said shaft slidable in the respective cams, means to reciprocate the cross-head, and independent mechanism controlled by each rod for disengaging the corresponding cam from said rod after the latter has moved up to a determinate extent.

18. In a machine for loading shells, the combination with a series of independent tamping rods, of a series of cams fulcrumed to rock in the direction of extension of the tamping rods, said cams having curved faces adapted to engage and reciprocate the tamping rods but permitting the latter to slip upward under predetermined resistance to downward movement, a cross-head, guides in which said cross-head reciprocates vertically, a shaft carried by said cross-head, blocks on said shaft slidable laterally in the respective cams, movable blocks on which said cams are respectively fulcrumed, a driving shaft, an eccentric thereon, a connecting rod between said eccentric and said cross-head, and independent mechanism controlled by each rod for moving the corresponding last-named block away from its corresponding rod after the latter has moved up to a determinate extent.

45 19. In a machine for loading shells, the combination with a series of independent tamping rods, of a series of cams fulcrumed to rock in the direction of extension of the

tamping rods, said cams having curved faces adapted to engage and reciprocate the tamping rods but permitting the latter to slip upward under predetermined resistance to downward movement, means to rock said cams, slidable blocks on which said cams are respectively fulcrumed, a pair of toggle levers jointed to each pair of blocks, and independent mechanism controlled by each rod adapted after said rod has moved up to a determinate extent, to move the corresponding pair of toggle levers toward a straight line position, thereby retracting the corresponding blocks and moving the corresponding cams out of operative position.

20. In a machine for loading shells, the combination with a series of independent tamping rods, of a series of cams fulcrumed to rock in the direction of extension of the tamping rods, said cams having curved faces adapted to engage and reciprocate the tamping rods but permitting the latter to slip upward under predetermined resistance to downward movement, means to rock said cams, slidable blocks on which said cams are respectively fulcrumed, means to rock said cams, springs tending to move said blocks and cams into operative relation with the tamping rods, a pair of toggle levers jointed to each pair of blocks, independent mechanism controlled by each rod adapted, after said rod has moved up to a determinate extent, to move the corresponding pair of toggle levers toward a straight line position, thereby retracting the corresponding blocks and cams, and means operated from a common control to simultaneously move all the toggle levers away from a straight line position, thereby causing all the blocks and cams to be restored to operative position.

In testimony of which invention, I have hereunto set my hand, at Wilmington, Del., on this 25th day of August, 1911.
